UNITED STATES PATENT OFFICE.

PAUL G. WAGNER AND ARTHUR ANDERSEN, OF LOS ANGELES, CALIFORNIA.

WRIST-PIN LOCK.

Application filed September 29, 1924. Serial No. 740,574.

To all whom it may concern:

Be it known that we, PAUL G. WAGNER and ARTHUR ANDERSEN, both citizens of the United States, and residents of the city of 5 Los Angeles, in the county of Los Angeles and State of California, have invented new and useful Improvements in Wrist-Pin Locks, of which the following is a detailed specification.

10 This invention relates to improvements in devices for releasably locking wrist pins within pistons of internal combustion engines and the like.

As is well understood, wrist pins comprise 15 the connecting elements between pistons and connecting rods, and due to the vibratory stresses occurring at this point of connection, it is necessary to provide positive means for retaining the removable wrist pins from 20 rotary and longitudinal movement. Where the retention means is of a character to become loosened under vibration, the pins have a tendency to work out of the supporting piston bosses until the pin ends bear against 25 the cylinder walls. As wrist pins are usually made of steel their end engagement tends to cut grooves in the softer cast iron walls of the cylinders, a most harmful occurrence. Furthermore, loose wrist pins 30 rapidly wear the piston bosses, and the resulting play or slap is very apt to have disastrous results, as is well understood by those skilled in the art.

Various types of wrist pin locks have 35 been employed, most of them in the form of set screws threaded through the piston bosses and projecting into seats or grooves in the wrist pins. However, these set screws tend to jar loose under repeated vibratory 40 stresses, resulting in wrist pin looseness and its attendant undesirable results. It has therefore become customary to lock the set screws by such means as check nuts, cotter keys, or the like, but due to the structural 45 characteristics of pistons, it is a most aggravating and tedious task to apply such locking means, and after their application they often fail in their function.

Other types of locking means, well known 50 to those skilled in the art, depending, for instance, on wedge or spring action, are often employed, but they are all of comparatively low efficiency, either due to their failure to hold or to the difficulty of ap-

plying and removing them. They have the 55 common disadvantage of allowing wrist pin play the instant the locking means develop wear, this play rapidly increasing until it reaches the danger point, as outlined above.

Therefore, it is the principal object of 60 our invention to provide a locking device which shall be positive in its locking action and yet is capable of being applied and removed with maximum ease. It is particularly applicable to hollow wrist pins, and the releasable means for retaining the lock member in position is located within the 65 wrist pin bore. Then we provide means for automatically taking up all wear which may develop between the wrist pin and locking pin, a feature of great value, as it constantly maintains the locking device fully 70 effective throughout the period of its useful life.

A better understanding of the invention 75 will be had from the following detailed description, reference being made to the accompanying drawings, in which:

Fig. 1 is a sectional view of a piston showing a wrist pin locked therein by our device;

Fig. 2 is an enlarged section, partly in elevation, taken on line 2—2 of Fig. 1;

Fig. 3 is a section, partly in elevation, on line 3—3 of Fig. 2;

Fig. 4 is a view similar to Fig. 2 but showing a modified form of locking device;

Fig. 5 is a view similar to Fig. 2 but showing another modified form of locking device; and

Fig. 6 is a section on line 6—6 of Fig. 5.

In the drawings, numeral 10 designates a piston having diametrically opposed, internal bosses 11 and 11^a which provide end support for hollow wrist pin 12.

Connecting rod 13 has bearing on pin 12 in the usual manner. Our locking device may be applied to pin 12 at either or both ends, but we find that its application to but one end suffices to securely lock the wrist pin, and we have therefore illustrated and will describe it only in connection with boss 11.

Boss 11 has a depending projection 14 having a bore 15 which extends radially 105 with respect to boss bore 16, while pin 12 has an aperture 17 preferably of smaller diameter than bore 15 but adapted to be

brought into axial alinement therewith when the wrist pin is in operative position within the piston.

A tubular locking pin 18, having a finger grip flange 19 has sliding fit within bore 15 and has a tapered inner end 20 adapted to seat within wrist pin aperture 17 and to maintain said aperture in axial alinement with boss bore 15.

10 Longitudinally slidable through the bore of locking pin 18 is a plunger 21, one end 22 thereof, being headed while the other end 23 is adapted to extend through aperture 17 and to project into wrist pin bore 12^a.

15 Preferably, though not necessarily, pin 18 is counterbored at 24 to provide a pocket for spring 25, said spring encircling plunger 21 and being interposed between plunger head 22 and pin shoulder 26.

20 Plunger end 23 has a transversely extending slot 27 which is of sufficient height to admit key 28 thereto, the upper edge of said key being centrally notched at 29 while the lower edge 30 of the key is adapted to span aperture 17 and to engage the bore defining wall of the wrist pin at opposite sides of said aperture.

In assembling the device, locking pin 18 is entered in bore 15, taper 20 projecting into aperture 17. Spring 25 is placed about plunger 21 and the plunger thrust through the bore of pin 18, spring 25 yieldably resisting this telescopic movement to such an extent that considerable pressure is needed to thrust plunger end 23 into pin bore 12^a. Plunger 21 is moved inwardly until notch 27 is fully presented within bore 12^a, whereupon key 28 is passed through the open end of bore 12^a and slipped through notch 27 into the position illustrated. Manual pressure on plunger 21 is then relieved, and spring 25 acts to draw plunger end 23 into key notch 29, wings 29^a at either side of the notch preventing longitudinal displacement of the key.

Key 28 prevents accidental withdrawal of plunger 21 and hence pin 18, and spring 25 both holds key 28 in engagement with the wrist pin and draws pin taper 20 into firm seating engagement with the wrist pin to prevent both longitudinal and rotary movement of said pin with respect to boss 11.

Of course, the described procedure of assembly need not be followed exactly. For instance, pin 18, plunger 21 and spring 25 may be assembled exteriorly of the piston and thrust, as a unit, into operative position.

Spring 25 constantly urges taper 20 into seating engagement with the wrist pin to take up any wear which may develop between the locking device and the wrist pin. The spring also takes up wear developing in the locking elements themselves, with obvious advantage.

60 In order that there may be no interference

between pin 18 and key 28, tapered end 20 is notched at 31. Of course, when end 20 is not of sufficient length to extend into bore 12^a, notch 31 need not be provided.

It is not necessary that bore 15 and aperture 17 be in exact axial alinement when the locking device is attached; it is only necessary that they be in such alinement that plunger 29 may be thrust through aperture 17 to allow the positioning of key 28. Then, 75 when the piston is jarred or reciprocated, taper 20 will be gradually moved through aperture 17 by spring 25 and will finally bring said aperture into axial alinement with bore 15.

In Fig. 4 we have shown a modified form of locking device wherein locking pin 18^a is solid and has no movable plunger corresponding to 21. The reduced end 32 of pin 18^a is slotted at 33 similarly to the end of plunger 21, the slot being adapted to receive key 28^a, similar to key 28. Spring 25^a encircles pin 18^a and is interposed between pin head 19^a and boss projection shoulder 34. Pin 18^a is adapted to extend through boss bore 15^a to bring end 32 through wrist pin aperture 17^a, spring 25^a and key 28^a serving to hold pin 18^a from longitudinal displacement.

In Figs. 5 and 6 we have illustrated a modified form of plunger and key. Such parts as are similar to or have the function of corresponding parts of Fig. 2 are numbered similarly except that the reference numerals of Figs. 5 and 6 are given the exponent b.

Plunger 21^b has an annular head 35, and after tubular pin 18^b, plunger 21^b and spring 25^b have been assembled, head 22^b is riveted in place against plunger shoulder 36 to hold the several elements in assembly.

Key 28^b is in the form of a disc which is drilled at 37 to receive the shank of plunger 21^b and counterbored at 38 to receive plunger head 35. Slot 39 opens to bore 37 so, after the locking device has been entered in apertures 15^b and 17^b and after the plunger has been thrust upwardly a sufficient distance into bore 12^c of wrist pin 12^c, the key may be slipped beneath plunger head 35.

Then when the manual pressure on the plunger is relieved, spring 25^b acts to draw plunger 21^b downwardly, seating head 35 in countersink 38 to hold the key against accidental displacement. The key functions in the same manner as key 28, but since its lower, flat face is spaced above aperture 17^b (due to the arcuate characteristic of the defining wall of bore 12^c) tapered end 20^b of pin 18^b need not be slotted nor notched even though said end projects slightly into bore 12^c.

It will be understood that various changes in design, structure and arrangement may be made without departing from the spirit 130

and scope of the appended claims, and therefore we do not wish to be limited except for such limitations as a fair interpretation of said claims may import.

5 Having described a preferred form of our invention, we claim:

1. In a device for locking hollow wrist pins in piston bosses, a locking pin adapted to extend radially through one wall of the 10 piston boss and into a registering wrist pin aperture, said aperture opening into the wrist pin bore, releasable means associated with said locking pin and arranged within the wrist pin bore, said means being adapted 15 to engage the wrist pin in a manner to hold the locking pin against withdrawal, and yieldable means for holding said releasable means in engagement with the wrist pin.

2. A device for locking a hollow wrist pin 20 in a piston boss, the pin and boss having radially extending, registering apertures, the boss aperture opening to the exterior of the boss and the wrist pin aperture opening to the wrist pin bore, a tubular locking pin 25 adapted to be entered through the boss aperture and to engage the wrist pin, a longitudinally slidable plunger within the bore of the locking pin and extending into the wrist pin bore, releasable means within the wrist 30 pin bore for holding the plunger against withdrawal, and yieldable means between the locking pin and plunger for maintaining the locking pin in engagement with the wrist pin.

3. A device for locking a hollow wrist pin 35 in a piston boss, the pin and boss having radially extending, registering apertures, the boss aperture opening to the exterior of the boss and the wrist pin aperture opening to the wrist pin bore, a tubular locking pin 40 adapted to be entered through the boss aperture and having a tapered extremity adapted to seat within the wrist pin aperture, a longitudinally slidable plunger within the bore of the locking pin and extending into the wrist pin bore, releasable means within the wrist pin bore for holding the plunger against withdrawal, and yieldable means between the locking pin and plunger for maintaining the tapered extremity of the locking 45 pin seated within the wrist pin aperture.

4. A device for locking a hollow wrist pin 50 in a piston boss, the pin and boss having radially extending, registering apertures, the boss aperture opening to the exterior of the boss and the wrist pin aperture opening to the wrist pin bore, a tubular locking pin 55 adapted to be entered through the boss aperture and having a tapered extremity adapted to seat within the wrist pin aperture, a longitudinally slidable plunger within the bore of the locking pin and extending into the wrist pin bore, a releasable key for the plunger and adapted to engage the inner 60 wall of the wrist pin at the sides of the wrist

pin aperture, and yieldable means between the pin and plunger adapted to maintain said key in engagement with the wrist pin and to maintain the tapered extremity of the locking pin seated within the wrist pin 70 aperture.

5. A device for locking a hollow wrist pin in a piston boss, the pin and boss having radially extending, registering apertures, the boss aperture opening to the exterior of the boss and the wrist pin aperture opening to the wrist pin bore, a tubular locking pin 75 adapted to be entered through the boss aperture and to engage the wrist pin, a longitudinally slidable plunger within the bore of the locking pin and extending into the wrist pin bore, a releasable key for the plunger and adapted to engage the defining wall of the wrist pin bore, and spring means connecting the locking pin and plunger in a 80 manner to maintain the plunger and key in assembly and to maintain said locking pin in engagement with said wrist pin.

6. A device for locking a hollow wrist pin 85 in a piston boss, the pin and boss having radially extending, registering apertures, the boss aperture opening to the exterior of the boss and the wrist pin aperture opening to the wrist pin bore, a tubular locking pin 90 adapted to be entered through the boss aperture and to engage the wrist pin, a longitudinally slidable plunger within the bore of the locking pin and extending into the wrist pin bore, a head on the extension of the plunger, a removable key adapted to coact 95 with said head and the wrist pin in a manner to hold the plunger from withdrawal from the wrist pin bore, and spring means connecting the locking pin and plunger to maintain the plunger and key in assembly 100 and to maintain said locking pin in engagement with the wrist pin.

7. A device for locking a hollow wrist pin 105 in a piston boss, the pin and boss having radially extending, registering apertures, the boss aperture opening to the exterior of the boss and the wrist pin aperture opening to the wrist pin bore, a tubular locking pin 110 adapted to be entered through the boss aperture and having a tapered extremity adapted to seat within the wrist pin aperture, a longitudinally slidable plunger within the bore of the locking pin and extending into the wrist pin bore, a head on the extension of the plunger, a removable key adapted to coact 115 with said head and the wrist pin in a manner to hold the plunger from withdrawal from the wrist pin bore, and spring means connecting the locking pin and plunger to maintain the plunger and key in assembly 120 and to maintain the tapered extremity of the locking pin seated within the wrist pin aperture.

8. A device for locking a wrist pin in a 125 piston boss, the pin and boss having radially

extending, registering apertures, the boss aperture opening to the exterior of the boss, a tubular locking pin adapted to be entered through the boss aperture and to engage the wrist pin, a longitudinally slidable plunger within the bore of the locking pin and extending into the wrist pin aperture, releasable means for holding the plunger against withdrawal, and yieldable means between

the locking pin and plunger for maintaining the locking pin in engagement with the wrist pin.

In witness that we claim the foregoing we have hereunto subscribed our names this 19 day of September 1924.

PAUL G. WAGNER.
ARTHUR ANDERSEN.
